CLOSURE FOR CANS

Letcher O. Grice, United States Army,
Washington, D. C.

Application March 13, 1942, Serial No. 434,516

7 Claims. (Cl. 222—488)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to portable containers for liquids and more particularly to a novel and improved type of closure adapted for use on portable containers such as gasoline cans.

It may be explained that in the present day type of modern warfare it is considered impractical to attempt to refuel all of the thousands of motorized vehicles in a modern mechanized division by any of the conventional stationary types of gasoline dispensing pumps and that the preferred practice adopted by the United States Army, and almost universally adopted by all of the major armies of the world, is to refuel the equipment from relatively small containers, each having a capacity of about five gallons. This system of refueling proposes marked advantages in that it makes it entirely unnecessary to bring large tanks, tank cars, et cetera, into the front lines where they are obvious and vulnerable targets for enemy bombardment, and substitutes the use of thousands of the relatively smaller containers that may be transported in ordinary motor vehicles and in smaller quantities, so that they are not so obvious as targets for the enemy and also so that they are not equally vulnerable even though struck by enemy fire.

It is believed the advantages of the use of small cans as pointed out in the paragraphs above are too well known to require any extended description, and it is mentioned in this application only to point out that while such a practice is regarded as essential and had been universally adopted, it has at the same time given rise to other problems of great importance that must be satisfactorily solved if the maximum efficiency is to be gained from the use of the small containers. Thus, in the use of any containers of this type, it is essential that they be arranged so that they are entirely leak-proof during handling and shipping and so that they may be opened or closed almost instantaneously. In addition, they must be of such a rugged construction that they are capable of withstanding the extremely rough treatment received by military equipment in the field.

The importance of any structure that will combine extreme ruggedness with instantaneous opening and closing should be fully appreciated when it is recalled that the operation of a single mechanized division, on maneuvers or during actual combat, requires thousands of gallons of

fuel for a single day and that in such typical operations of the kind it is customary to refill 20,000 of the five-gallon cans at a single railhead each night, in order to maintain an adequate supply of fuel.

It is, therefore, the principal object of the present invention to provide a novel and improved closure for portable liquid containers, the closure being of such design and construction that it may be fully opened or sealed in closed position almost instantaneously and without the use of any wrenches, levers, keys or tools of any description.

A further object of the invention is to provide a novel and improved container closure including a hinged cap adapted to seat on a sealing flange, cam anchoring means associated with the flange and a novel and improved cam operating plate including a relatively flat top surface, flat side surfaces and internal flange cams so arranged that they are inside of the plane of the side surfaces and below the plane of the top surface and are thus protected from accidental damage.

A further object of the invention is to provide an improved container closure including a sealing flange cap and cam handle including a wide flat grip portion designed to permit the cam to be lifted by the grip portion of the handle so that no type of latching means or auxiliary support is required to hold the cap of the container open during the pouring operation.

A further object of the invention is to provide a novel and improved container closure including a locking cap and a cam operating lever having a bifurcated end portion so arranged that the two ears of the end portion of the cap lie between and below the upper plane of a triple handle, so that the cam locking plate will be protected against accidental damage due to any impacts from external sources and yet so that the ears may be accessible and easily lifted in order to open the container without the use of tools.

A further object of the invention is to provide a novel closure adapter for liquid containers so that a conventional screw-threaded flange type of closure may be readily converted to include all of the advantages above pointed out and may be at the same time provided to receive a screw-threaded flexible spout having threads of the same pitch and diameter as the threads of the cam flange.

A further object of the invention is to provide a novel and improved container closure including a closure cap, a cam locking means, and a cam operating lever having a cutaway portion

and internal bead such that the cam operating lever may be used as a handle for lifting the container, in combination with a latching means adapted to latch the cam operating plate against the cap and thus prevent the release of the cam locking device.

Referring now more particularly to the drawings:

Fig. 1 is a side elevational view of the top portion of a standard Army fuel can showing the improved container closure to which the present invention relates;

Fig. 2 is a fragmental top plan view of the container and the closure;

Fig. 3 is an enlarged central detail sectional view through the structure of the closure;

Fig. 4 is a perspective view of the lower side of the cam locking lever;

Fig. 5 is a perspective view of the container closure in closed position;

Fig. 6 is a perspective view of the container closure in open position, and

Fig. 7 is a view taken on the line 7—7 of Fig. 2.

In the illustrations of the present application, the improved form of container closure is shown as attached to a standard Army gasoline container which is of generally rectangular shape including relatively flat sides 11 and 12 joined to the narrow end portions 13 and 14 by rounded corners 15.

As shown in the drawings, the top 16 of the container is made of a single piece of sheet metal formed into the desired shape and united to the body of the can 17 by a rolled or welded bead 18 extending completely around the can. The top portion 16 of the can is drawn from a single piece of sheet metal, as pointed out above, and is shaped to include a hump 21 at one end. A closure flange 22 is provided at the other end and is mounted on an inclined portion 23 of the can top. The inclined portion 23 on the sealing flange 22 are both positioned at an acute angle with respect to the horizontal and at a level substantially below the top of the hump 21.

The center portion of the can is formed as a relatively horizontal portion 24 extending from the lower edge of the hump to the upper edge of the inclined portion 23.

The container is also provided with a triple handle structure which, in the present drawings, is shown as being formed of a single piece of sheet metal, divided to provide three separate handles extending from a point adjacent the upper end of the inclined portion 23 to the top of the hump 21. This handle includes a flange 25 adapted to lie flat against the upper end of the inclined portion 23 and welded onto portion 23 in order to secure the forward end of the handle. The flange 25 is folded at 26 and extends upwardly in a forward web portion 27, and this web 27 is trifurcated at its upper end to provide three separate horizontal handle portions 28, 29 and 30 each of which is rolled from the sheet metal of which the structure is constructed so that each is substantially cylindrical in shape.

It will be noted from Figs. 2, 5 and 6 that portions of the web 27 between the handles 28, 29 and 30 are cut away along a gradual curve extending well below the plane of the top of the handles. (See Fig. 6.)

The container is also provided with an internal vent tube 35 welded into the threaded flange 22 at the point 36 to establish a vent port 37 on the upper flat surface of the threaded flange. The opposite end of the vent tube 35 extends into

the hump 21 of the container to provide an unobstructed air inlet when liquid is being poured from the mouth of the container.

The container as thus far described may be sealed by standard flanged screw-type closures, if desired, and the screw threads of the flange 22 also adapt this container to receive a screw-threaded plug on which a long flexible metallic spout is mounted to facilitate the discharge of the liquid within the container into inaccessible filling pipes on various different kinds of motorized equipment.

It is a particular object of the present invention, however, to provide an adapter structure arranged to be attached to the conventional screw-threaded flange and to convert the container from one in which the operation of the screw-threaded cap was necessary to open or close the can to one in which the opening and closing could be accomplished practically instantaneously and without tools by merely lifting a cam operating plate or forcing it downwardly into locked position. To this end the present invention provides an auxiliary cup 41 having an internal flange 42 at its lower end. The lower flange 42 of the cup is adapted to be clamped into sealing engagement with the upper surface of the screw-threaded flange 22 of the container by a shoulder portion 44 on a central sleeve 43, and arranged to clamp against the upper surface of the flange 42. The sleeve 43 is provided with a plurality of internal lugs 45 so that it may be tightly clamped into position, and a sealing gasket 46 is located between the internal flange 42 of the cup and the flat surface of the flange 22 to provide a permanent seal at this point. The flange 42 of the cup 41 includes a small opening 47 which is adapted to register with the vent opening 37, and the gasket is perforated to establish an air connection for the vent. Preferred, the orifice in the center of the flange 42 is not concentric with the cap 41 but is located closer to the lower edge of the cup, so that the upper edge will have a wider surface and will provide unobstructed access to the vent tube. The sleeve 43 is provided with an upwardly extending pouring spout 48 having internal screw threads 49 of the same pitch and diameter as the screw threads of the threaded flange 22 of the can.

Thus, if desired, any flexible type of pouring spout provided for insertion into the conventional threaded flange may be received in the screw threads 49 to facilitate the pouring of the liquid into fuel lines that are extremely difficult to reach. It is not regarded as essential, however, to provide such a pouring spout since the upper end of the pouring spout 48 lies above the plane of the upper extremity of the cup 41 and (since it has already been pointed out that the cup 41 is concentrically mounted) the space 51 between the pouring spout 48 and the cup 41 is so small that the stream of liquid will readily flow from the upper edge of the spout 48.

The upper end of the cup 41 is provided with a flat outwardly extending sealing flange 52 in order to establish a sealing surface for the container cap 61 to seat against.

The flange 52 is arranged to include an extension 53 terminating in a loop 54 to support a pivot pin 55 on which the closure cap 61 is mounted, and two side extensions 56 terminate in rounded cam anchor portions 57 extending downwardly slightly below the plane of the sealing flange 52 and closely adjacent the side walls of the cup 41. The closure cap 61 is formed in

a generally circular shape including a downwardly extending flange 62 and a rearwardly extending web 63 terminating in a pair of ears 84 mounted on the pivot pin 55 heretofore described. The downwardly extending flange 62 is notched at both sides by the notches 65 and 66 to provide clearance for the cam anchoring means 58 and 59, respectively, and a sealing gasket 67 is mounted in an annular flanged gasket cup 68 so that it will bear against the upper sealing surface of the flange 52 and will seal the entire cup against egress of fluid when the cap is forced down against the upper flange of the cup. The cap is clamped against the cup by novel cam operated structure including a particular configuration of cams so designed that the cam surfaces are well protected against accidental damage. These include a cam operating plate of novel design and construction whereby it is well adapted to exert comparatively large forces against the cams to effect tight sealing of the container and equally adapted to be easily clamped and released without the use of tools.

Further, the cam locking plate is designed to include a handle arranged so that the entire container may be lifted by the locking plate, so that the container may be gripped by the locking plate while the liquid is being poured from the spout in order to hold the cap in open position without any auxiliary types of retainers.

A cam operating plate 71 is mounted on a cross pin 72 welded to the top of the cap 61 at 73 and the plate is formed of a relatively flat central section 75 and two downwardly extending side webs 76 and 77, one positioned on either side of the cap 61. This structure gives great rigidity to the cam locking plate since the opposite side edges 78 and 79 constitute the corners of the folded metal sheet and thus have relatively great strength, so that the mechanism is adapted to resist heavy impacts from external sources without damage either to the cam locking plate or to the closure structure all essential parts of which are protected by the plate. The locking means, themselves, comprise internal flanges 81 and 82 each extending inwardly from the lower surface of the webs 76 and 77, respectively, and positioned to ride under the cam anchors 58 and 59 respectively, and to exert a cam action to force the cross pin 72 and the cap 61 downwardly into firm sealing engagement with the flange 52 of the cup 41. Thus, to seal the container, it is only necessary to pivot the cap 61 downwardly above the pivot pin 55, engage the cams 81 and 82 under the cam anchors 58 and 59 respectively, and force the cam plate downwardly against the container cap to the position shown in Figs. 3 and 5.

It may be well to point out that although this function may be accomplished entirely without the use of tools, yet it is possible and entirely feasible to exert a great degree of force on the cam surfaces since the rearward end of the cam locking plate 71 includes a relatively flat, broad smooth surface 83 on which the operator may exert substantial force without injuring his hands.

The cam locking plate 71 is bifurcated at its extreme end to provide a pair of ears 84 and 85, and each of these ears is arranged to assume a position between two of the adjoining handle portions of the container and slightly below the upper horizontal surface of the handles (see Figs. 3 and 5). These ear portions are particularly useful in releasing the cams and opening the con-

tainer closure since they project well beyond the upper end of the forward web 27 of the handles so that there is unobstructed clearance below the ears 84 and 85 and between the handle portions 28, 29 and 30. With this structure the operator may reach between the handles and firmly grip either or both of the ears 84 and 85 to lift the locking plate, and can obtain a good mechanical advantage over the cam surfaces. Since the ears are at the extreme ends of the locking plate, it will be obvious that a relatively large amount of force may be exerted by use of the bare hands and that no types of tools will be required to release the cams and open the container.

10 In numerous types of container closures of the general class to which the present invention relates, the inventors have provided some type of slotted pivots, or similar connection, between the cap and the body of the container in order to maintain the cap in open position while the fluid is being poured from the container. It is obvious, of course, that some provision must be made for maintaining the cap in open position at this time, but the structures known to the 15 applicant have been entirely unacceptable for military use by reason of the fact that they latch or otherwise secure the cap in some position extending angularly outwardly from the body of the container, and so located that the structure is 20 extremely delicate and very subject to damage from rough handling of the containers. That is, if the cap is maintained by any type pivot that will resist closing movement, the cap may be 25 damaged beyond immediate repair if dropped or 30 thrown from the top of a tank onto a hard surface.

The present invention overcomes this difficulty by providing the cup with a simple form of pivot, namely, the pivot pin 55 which will always yield 40 to forces tending to close the cap against the mouth of the container, but the cap may be held open during the filling operation by the simple expedient of supporting the can during pouring by gripping the top of the can by the cam locking 45 plate 71. To facilitate this operation, the locking plate 71 is cut away between the side webs 76 and 77 to provide a central recess 86, and the rearward edge of the recess is provided with a rolled bead 87 to afford a comfortable hand grip.

50 From an examination of Figs. 2 and 5, it will be seen that the side plates or webs 76 and 77 co-act with the transverse rolled bead 87 to provide a structure that is, in effect, a bail type handle pivoted on the cross rod 72. Thus, the operator 55 may support the container by the bail so that the cap will be held in completely open position during the pouring operation but will be free to pivot back into locked position whenever the cam plate 71 is released.

60 Under all ordinary conditions of use, the structure thus far described comprises an entirely complete closure mechanism. The friction inherent in the cam surfaces prevents the release of the cam plate unless positive force is exerted 65 to raise the plate, and it is therefore contemplated that no additional type of latching mechanism is ordinarily required to maintain the cap against release. Under certain circumstances it may be desirable, however, to equip the closure 70 with an additional auxiliary latching device and, when so desired, the present structure is well adapted to accommodate such a latch by merely providing a pivoted latch hook 91 on a pivot pin 92 extending through the rolled bead 87 of the 75 cam locking plate 71. To accomplish this, the

bead 87 is notched or slotted with a slot 93 approximately one-third of the distance across the length of the bead and the latch hook is provided with a coiled wire spring 94 so that its lower end may engage the under surface of the web 63 of the closure cap and prevent the latch plate from being raised. A latch release lug 95 extends outwardly into the cavity 86 so that the latch may be released by moving the lug 95 downwardly against the pressure of the latch spring 94 and a perforation 96 is provided in the web 63 of the closure cap so that the web will not obstruct the operation of the latch.

It has been stated above that this structure is regarded as auxiliary in nature rather than an essential element of the present invention, but, inasmuch as it may be desirable, under certain conditions, it is illustrated in connection with the present case, and it may be pointed out also at this time that when the design is illustrated in the present drawings it does not hinder the use of the latch plate as a carrying bail or as a handle during pouring since the normal width of the bead 87 is of proper dimensions to accommodate three of the operator's fingers and the latch is positioned approximately one-third of the way across the bail so that the operator may place two fingers on one side of the latch and one finger on the other and may handle the container with complete freedom of any interference from the latch structure.

From the foregoing description, it is believed apparent that the present closure structure provides a simple mechanism of great utility and unquestionable value in that it accomplishes all of the above mentioned objects of the present invention by the use of a mechanical structure adapted to mass production methods of manufacture, easy to install, practically instantaneous in operation, and at the same time of a mechanical design well adapted to resist the rough handling and abuse that structures of this character must necessarily withstand in the field, when in use by troops.

The present invention has been developed in the United States Army and adopted by the Army as the most successful device of its character yet devised, but while it is particularly adapted to military use and has been designed essentially for military purposes, it is believed to have utility in commercial fields as well, and it is therefore requested that the scope of the invention be limited only by the limitations of the appended claims.

Having thus described my invention, I claim:

1. In a portable container, in combination, a container top portion including a relatively horizontal central section terminating at one end of a hump extending well above the horizontal plane of the central section and located closely adjacent the end wall of the container, and at the other end terminating in a downwardly inclined relatively flat surface lying at an acute angle with respect to a horizontal plane and having a container mouth therein, a handle structure formed of a single, integral sheet of metal, said handle portion including a flange secured to the upper end of the inclined portion of the can top, a web extending upwardly from said flange and three tubular handle elements extending from the web to the hump, and a container closure comprising a pivotally mounted sealing cap for the container mouth and a cam means interconnecting the container cap and container mouth, said cam means including a pivoted cam locking lever having ear

portions at the end remote from the pivot, said ear portions being of a width less than the spaces between said handle elements, said ear portions lying between the handle elements and below the upper surface of the handle structure when the cap is locked in closed position and said lever when unlocked serving as a bail to support the container in pouring position while at the same time holding the cap open.

10 2. In combination, a container having a rectangular top having one end sloped downwardly and provided with a dispensing outlet on said sloped end and the other end raised, a plurality of spaced handles extending across the top from the raised portion to the upper side of the sloped portion, and a hinged cap and cap locking assembly mounted adjacent the dispensing outlet with the cap hinge adjacent said outlet, said hinge lying between the dispensing opening and the adjacent ends of the handles, and a cam locking plate hinged to the body of the cap and having extensions lying between the container handles and protected thereby when the plate is in locking position.

25 3. In combination, a container having an internally-threaded outlet adjacent one side of its top and a raised handle extending across the central portion of the top and a combined spout and pivoted closure for the outlet comprising a cup member having an internally extending bottom flange resting on the rim of the outlet and having external cam anchors at its top, a sleeve threaded into the outlet and having an external shoulder to secure the cup flange on the rim and projecting above the cup to form a pouring spout, a cap hingedly mounted on the cup on the side adjacent the container handle, and a cam locking plate pivoted on the cap and adapted to be pressed down into cam engaging position on the side toward the hinge, said plate being bifurcated so as to lie on opposite sides of the handle and below the top thereof.

4. A combined spout and pivoted closure for a container having a screw-threaded opening comprising a cup member having an internal flange adapted to be secured to the rim of the opening, said cup member carrying cam anchor portions, a sleeve adapted to be threaded into the opening and having an external shoulder for securing the flange to the rim and a tubular extension forming a spout extending through the cup, a cap hingedly mounted on the cup member, and a bail-shaped cam locking plate pivoted on the cap and adapted to swing toward the hinge of the cap and having a pivoted latch for engaging the cap outside its hinge for holding the plate in cam anchor engaging position.

5. In combination, a container having an internally threaded outlet adjacent one side of its top and a raised handle extending across the central portion of the top and a combined spout and pivoted closure for the outlet comprising a cup member having an internally extending bottom flange resting on the rim of the outlet, a sleeve threaded into the outlet and having an external shoulder to secure the cup flange on the rim, a cap hingedly mounted on the cup member on the side adjacent the container handle and interlocking cam means on the cup member and cap including a bail-shaped cam locking plate pivoted on the cap and adapted to swing toward the hinge of the cap for locking said plate and when unlocked serving as a second handle to support the container in pouring position while at the same time holding the cap open.

6. In combination, a container having an internally screw-threaded opening provided with a raised rim, a vent tube attached to and opening through said rim and a hinged cap assembly mounted in said opening and comprising a cup member having an internally extending flange abutting said rim and provided with an aperture in alignment with said vent, a sleeve threaded into said opening and having an external shoulder holding said flange on said rim, and a hinged cap mounted on said cup member and closing its outer end.

7. In combination, a container having a rectangular top provided with a filler neck, an ex-

10 tension from one side of said neck terminating in a hollow hinge bead, a hinge pin in said bead, and a cap and cap locking assembly hingedly mounted on said hinge pin, said cap having an extension formed with downwardly turned ears to receive said hinge pin, a cam locking plate hinged to the body of the cap, said plate having a grip portion overlying the cap hinge in locked position of the plate, and a latch pivoted on the grip portion and adapted to latchingly engage the cap extension at its outer end when the cap is in locked position.

LEITCHER O. GRICE.
